United States Patent

Des. 240,437
Patented July 6, 1976

240,437

MODEL GLIDER

Earl Rizzo, Lakewood, Ohio, assignor to
Cosmo, Inc., Cleveland, Ohio

Filed July 10, 1974, Ser. No. 486,957

Term of patent 14 years

Int. Cl. D21—01

U.S. Cl. D34—15 HH

FIG. 1

FIG. 2

FIG. 3

FIG. 4

FIG. 5

FIG. 6

FIG. 1 is a top plan view of a model glider showing my new design;

FIG. 2 is a bottom plan view thereof;

FIG. 3 is a front elevational view thereof;

FIG. 4 is a right front perspective view thereof;

FIG. 5 is a left side elevational view thereof; and

FIG. 6 is a rear elevational view thereof with the forward portions omitted for ease of illustration.

I claim:

The ornamental design for a model glider, as shown.
